**COMBINATION SUN CHRONOMETER, COMPASS,
AND SEMI-FLEXIBLE DISPENSING BOTTLE**

Milton P. Larsen, Los Angeles, Calif.

Application August 2, 1957, Serial No. 47,203

Term of patent 14 years

(Cl. D58—6)

Fig. 1 is a perspective view of the combination sun chronometer, compass and semi-flexible dispensing bottle showing the new design;

Fig. 2 is a side elevational view thereof;

Fig. 3 is a top view thereof; and

Fig. 4 is a cross-sectional view thereof taken on the line 4—4 of Fig. 1.

The rear of the article, not shown, is substantially plain.

The essential features of my design reside in the portions shown in full lines.

I claim:

The ornamental design for a combination sun chronometer, compass, and semi-flexible dispensing bottle, as shown and described.
